FILLING CATCHER

Charles Emile Pelletier, Suncook, N. H.

Application January 23, 1947, Serial No. 723,780

3 Claims. (Cl. 139—256)

1

The present invention relates to a filling catcher for looms and it consists in the combinations, constructions and arrangements of parts herein described and claimed.

It is an object of the invention to provide means for quickly cutting and removing loose threads from the raceboard cover of a loom.

A further object of the invention is to provide a tensioning for the first thread moving across a loom when there has been a change of bobbins.

In rayon weaving looms the raceboards are covered with materials such as mohair, felt, velvet or the like and the threads of the weft are very apt to become entangled with such material if not kept free from it. Another object of the present invention, is therefore, the provision of means for dropping off the loose weft threads completely out of the way of the raceboard cover.

Other and further objects of the invention will become apparent from a reading of the following specification taken in conjunction with the drawings, in which:

Figure 1 is a plan view of an embodiment of the invention.

Figure 2 is a view similar to Figure 1 but showing the invention in locked position.

Figure 3 is an enlarged plan view of the apparatus forming my invention.

Figure 4 is a side elevational view of Figure 3, and

Figure 5 is a sectional view taken along line 5—5 of Figure 3.

Referring more particularly to the drawings, there is shown therein my apparatus attached to the battery stand of a loom preferably by bolting the same thereto. The numeral 10 indicates a base which is fastened to the breast beam by the side of the battery stand of the loom in any suitable manner and it is provided with a pair of short vertically extending arms 11 in which is slidably mounted a rod 12. A detent or collar 13 is affixed to the rod between the arms 11 by means of a locking screw 14 and a coil spring 15 surrounds the rod and bears against the detent 13 at one end and against one of the arms 11 at its other end. The detent 13 is provided with a forwardly sloping top face 16.

The rod 12 is L-shaped being bent at a right angle and a vertically disposed leg 17 thereof carries a rearwardly projecting lay engaging stop 18 having an adjustable head 19 and is locked in position upon the rod 12 by means of a screw 20.

A filling hook 21 is provided with a shank 22 having an elongated slot 23 cut therein allowing

for its slidable engagement with a pair of bolts 24 carried by a filling hook arm 25 adjustably secured to the rod 12 by means of a screw 26. A spring 27 is mounted upon a pin 28 and its free end 29 is adapted to bear against the shank 22 of the filling hook 21.

A latch arm 30 is pivotally attached to the base 10 as indicated at 31 and is normally urged downwardly by a coil spring 32 also carried by the base 10. The arm 30 extends across the rod 12 and its associated spring 15 and thence rearwardly, terminating in a lip 33 having an opening 34 therein.

A vertically extending rod 35, adapted to be reciprocated by the uplift member 5 of the loom, is slidably mounted in the opening 34 and is provided with an adjustable stop member 36 above the opening 34 and a like member 37 at a point below said opening.

The arm 30 is cut away as indicated at 38 in Figure 5 for the reception of the upper half of the rod 12 and its associated spring 15 and in such manner as to provide a locking lip 39 for engagement with the squared end 40 of the detent 13.

Reference to Figure 2 will show the apparatus in locked position. The dotted lines 41 and 42 therein indicate the incoming and outgoing wefts caught by the filling hook 21. The filling hook 30 is unlocked by means of an upward motion of the rod 35 being actuated by the uplift mechanism of the loom which goes into action when a bobbin is about to be changed. Such upward movement of the rod 35 causes the stop 37 to impinge against the arm 30 allowing the detent 13 to move rearwardly by action of the spring 15 to the position shown in Figure 1.

The rod 12 and its associated parts, including the filling hook 21, are then moved back again by pressure applied on the lay engaging stop 18 coming into contact with the loom lay. Since the rod 35 has not completely returned to its normal position, the arm 30 will not lock with the detent 13 at this time but will allow the rod 12 to again return to its rearward position. Upon the loom lay again striking the stop 18, the rod 35 will have travelled completely back to its normal position and the detent 13 will now slide under the cut away portion 38 of the arm 30 and be again locked in the position shown in Figure 2.

The slidable mounting of the shank 22 of the filling hook 21 is a safety measure. If the hook should come into contact with the shuttle, no breakage will occur as the hook will move back

against the action of the spring 27 which will return it to normal position when the obstruction has moved on.

While but one form of the invention has been shown and described herein, it will be apparent to those skilled in the art that many minor modifications may be made without departing from the spirit of the invention or the scope of the appended claims.

What is claimed is:

1. In a filling catching attachment for a loom, the combination which comprises a base to be mounted on the breast beam of a loom, an L-shaped rod slidably mounted in the base and positioned with a vertically positioned leg thereof extended downwardly, a collar having a sloping surface on the forward end carried by the rod, a spring on said rod urging the collar rearwardly, a latch arm pivotally mounted on said base and extended across the L-shaped rod for locking the rod through the collar thereof, said latch arm positioned to be reciprocated vertically to unlock the said collar when the loom makes a bobbin change, an adjustable lay engaging stop carried by the vertically positioned leg of the L-shaped rod, a filling hook arm also carried by said L-shaped rod, a filling hook slidably mounted on said filling hook arm, and means urging said filling hook rearwardly.
2. In a filling catching attachment for a loom, the combination which comprises a base to be mounted on the breast beam of a loom, an L-shaped rod slidably mounted in the base and positioned with a vertically positioned leg thereof extended downwardly, a collar having a sloping surface on the forward end carried by the rod, a spring on said rod urging the collar rearwardly, a latch arm pivotally mounted on said base and extended across the L-shaped rod for locking the rod

through the collar thereof, said latch arm positioned to be reciprocated vertically to unlock the said collar when the loom makes a bobbin change, an adjustable lay engaging stop carried by the vertically positioned leg of the L-shaped rod, a filling hook arm also carried by said L-shaped rod, a filling hook slidably mounted on said filling hook arm, and means adjusting the said filling hook arm vertically on the said vertically positioned leg of the L-shaped rod.

3. In a filling catching attachment for a loom, the combination which comprises a base to be mounted on the breast beam of a loom, an L-shaped rod slidably mounted in the base and positioned with a vertically positioned leg thereof extended downwardly, a collar having a sloping surface on the forward end carried by the rod, a spring on said rod urging the collar rearwardly, a latch arm pivotally mounted on said base and extended across the L-shaped rod for locking the rod through the collar thereof, said latch arm positioned to be reciprocated vertically to unlock the said collar when the loom makes a bobbin change, and resilient means on the base 25 urging the said latch arm downwardly.

CHARLES EMILE PELLETIER.
